US00D572139S

(12) **United States Design Patent**
Trollope et al.

(10) **Patent No.:** **US D572,139 S**
(45) **Date of Patent:** **** Jul. 1, 2008**

(54) **BOTTLE**

(75) Inventors: **James D. Trollope**, Frisco, TX (US);
Blair C. Dugger, Frisco, TX (US);
Kendall L. Yorn, Allen, TX (US); **Alan Flude**, London (GB)

(73) Assignee: **Dr Pepper/Seven Up, Inc.**, Plano, TX (US)

(**) Term: **14 Years**

(21) Appl. No.: **29/295,175**

(22) Filed: **Sep. 21, 2007**

Related U.S. Application Data

(63) Continuation of application No. 29/249,392, filed on Oct. 4, 2006, now abandoned.

(51) **LOC (8) Cl.** **09-01**

(52) **U.S. Cl.** **D9/516; D9/552**

(58) **Field of Classification Search** **D9/682, D9/686, 688-693, 772-776, 516, 520, 537-540, D9/545-547, 549, 550-554, 556-558, 565-567, D9/569; 215/382-384, 396, 398; 220/669, 220/674-675**

(57) **CLAIM**

The ornamental design for a bottle, as shown and described.

DESCRIPTION

FIG. 1 is a top plan view of a bottle showing our new design;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a bottom plan view thereof.

The broken lines showing environment are for illustrative purposes only and form no part of the claimed design.

The curving, oblique shade lines shown in the drawings represent a transparent surface.
